The ornamental design for an airport-lighting taxiway curve, as shown and described.

DESCRIPTION

FIG. 1 is a top, front perspective view of an airport-lighting taxiway curve embodying my new design;

FIG. 2 is a top plan view thereof;

FIG. 3 is a front elevation view thereof; the rear elevation view being identical to that shown in FIG. 3;

FIG. 4 is an enlarged, cross-section detailed view taken along line 4-4 of FIG. 2; and,

FIG. 5 is an enlarged, cross-section detailed view taken along line 5-5 of FIG. 2.

The dash-dash broken line representations in the views are for the purpose of illustrating unclaimed environment of the claimed design. The dot-dash-dot broken line representations define unclaimed boundaries of the claimed design.
